UNITED STATES PATENT OFFICE.

JAMES H. REINHARDT, OF EAST ORANGE, NEW JERSEY.

PROFILE-GAGE.

1,261,438.

Specification of Letters Patent.

Patented Apr. 2, 1918.

Application filed June 20, 1914. Serial No. 846,286.

To all whom it may concern:

Be it known that I, JAMES H. REINHARDT, a citizen of the United States, and resident of East Orange, in the county of Essex and State of New Jersey, have invented certain new and useful Improvements in Profile-Gages, of which the following is a specification.

The object of my invention is to provide simple and efficient profile gages, and also to provide means to connect several of such gages together, in such manner that they may be used in a straight line or at angles to one another, as occasion may require, this being particularly useful where the profile is to be taken of an object that is longer than a gage.

My invention comprises novel details of improvement and combinations of parts that will be more fully hereinafter set forth and then pointed out in the claims.

Reference is to be had to the accompanying drawings forming part hereof, wherein, Figure 1 is a side view of a pair of profile gages, with means for connecting them together, for adjustment relative to one another, in accordance with my invention;

Fig. 2 is a partly broken side view, illustrating one of the profile gages in use, the gage being inverted with respect to Fig. 1;

Fig. 3 is an enlarged view, parts of the gage being removed;

Fig. 4 is a section through a complete gage taken on the line 4, 4, in Fig. 3;

Fig. 5 is an edge view of the gage;

Fig. 6 is a face view of a modification, one of the members being removed;

Fig. 7 is an enlarged section of a complete gage on the line 7, 7, in Fig. 6;

Fig. 8 is an enlarged face view, illustrating the use of my relatively large gages for measuring relatively large surfaces in conjunction with a smaller gage;

Fig. 9 is an edge view of the smaller gage shown in Fig. 8;

Fig. 10 is a cross section of Fig. 9, and Fig. 11 is a detail of the spacer hereinafter referred to.

Similar numerals of reference indicate corresponding parts in the several views.

My improved gage comprises two opposed clamping members or plates 1, 2, between which are slidably fitted parallel rods or pins 3. Members 1, 2, are clamped together by screws 4. As shown in Fig. 4, one of the members, as 2, has threaded projections

5 receiving screws 4, and in Figs. 6 and 7 projections 5 are stamped out of members 1, 2. The members 1, 2 are shown substantially in gutter-like form, whereby they may be made of relatively thin metal, and one or both of said members may be provided with teeth 6, along the margins or edges, to space and guide the rods or pins 3. Within the members, and frictionally bearing against rods or pins 3, is a retaining device indicated at 7. In Figs. 1 to 5 said retaining device is in the form of rubber tubes or webs 8 containing cores or rods 9 to somewhat stiffen them, although solid rubber tubes can be used. Said tubes are shown retained in gutter-like strips 10 spaced in one of the members. The gutters 10 may be formed in suitably bent strips of metal 11 riveted to the members, whereby said members are stiffened, and the strips 11 may be made of relatively thin metal. The retaining devices are of such dimensions as to bear snugly against the rods or pins 3, so that the latter will be retained in set positions, the marginal edges or teeth of member 2 bearing against said rods or pins serving to keep them in engagement with the retaining devices. As shown in Figs. 3 and 4 the retaining devices are enveloped in a protecting cloth covering 12, which is folded around said retaining devices, its edges being lapped and gummed together, (see Fig. 4). By this means the rubber of the retaining devices is kept from contact with the metal parts, and the retaining devices are kept in a unit.

In the form shown in Figs. 6, 7 and 10 the retainers 8 are in the form of a rubber mat, having longitudinal webs 8, and the rods 9 or pins 3 fit crosswise and in contact with such mat. A cloth strip 12 on the bottom of the mat protects it from the metal parts.

As so far described the profile gage may be used to take profiles of objects by placing the ends of the rods or pins against the object, and moving the pins into contact therewith, as illustrated in Fig. 2, and said rods or pins will be retained in set positions, so that the outline produced at the ends of the rods may be traced. In order to enable two or more of the profile gages to be attached together end to end, and utilized in a straight line, or at desired angles to one another, I provide the following means. Secured to the end one of the members, as 1, is a casting or the like 14, having threaded

holes 15 receiving screws 16, and at the opposite end of the other member, as 2, is secured a substantially corresponding casting 17, having slots 18, the projecting ends of 5 said members being adapted to fit with relation to one another, and the slots 18 being adapted to receive the screws 16, (Figs. 1 and 8), whereby said gages are secured together. The gages may be secured together 10 in a straight line as shown in Fig. 1, or may be secured together at an angle to one another, as indicated by the dotted lines in Fig. 1 and in Fig. 8. To this end one or both of the screws 16 may slide in the corresponding slot or slots 18, and then be set tight. By this means objects longer than a single gage may be readily outlined, whether 15 said objects be generally straight, or more or less curved or offset at places, since one or more of the gages may be set with respect 20 to one or more other gages to correspond to the general contour of the object, and then the rods or pins 3 of the respective gages may be pushed against the surface of the object, as required, to obtain its outline along 25 the ends of the rods or pins, whereby a pencil may be drawn along the ends of the pins to trace such outline or contour of the object. From such outlines objects corresponding 30 to the master object may be reproduced either in relief or concave according to which way the outline drawn from the ends of the rods is used. The gage may be retained set and utilized in the production of the work.

35 In order to further aid in keeping the rods or pins 3 in proper relative positions, side by side, I provide a relatively thin plate 21 (Fig. 11) having spaced projections or teeth 22 on its opposite edges, which are 40 adapted to pass between any desired number of the rods or pins. As a simple and efficient means for this purpose, and in order that the projections or teeth 22 may be quite thin, I have shown the strip 21 as provided 45 with angular cuts at 23 along its margins, whereby the projections or teeth 22 may be bent substantially at right angles to strip 21, and present thin spacing teeth between adjacent rods or pins 3. The strip 21 may be 50 carried by the member 1 or 2, in any desired manner. Strip 21 has appropriate holes 21^a for the passage of screws 4 or projections 5, or both. I have shown said strip 21 as riveted to one of the strips 11 opposed to the retainers 8 (see Fig. 4). This arrangement 55 serves to overcome the tendency of rods or pins 3 to roll upon one another and be displaced in use, as but a relatively few of such rods or pins need be between said pairs 60 of projections or teeth 23.

When two or more of the gages are secured together, as illustrated in Fig. 8, and set at an angle to each other, whereby an increased space 20 is caused between the opposing rods or pins of two adjacent gages,

a relatively small gage may be set in between said spaced rods and may be secured thereto by any suitable means, whereby the rods or pins of such smaller gage may be adjusted to profile the portion of the object 70 between such spaced pins of the main gages.

To this end I have shown one of the smaller gages (Figs. 8, 9 and 10) as provided with a clamping bar or the like 24, shown suitably bent to substantially inclose 75 or overlie the gage members, and having its ends 24^a extended over the projecting end portions 2^a of the lower member of the gage, to clamp therebetween rods or pins 3 of adjacent angularly disposed gages, as shown 80 in Fig. 8. To this end one of the smaller gage members is shown provided with a threaded stud 25, that passes freely through a hole in member 24 and is provided with nut 26 to cause the end portions 24^a of member 24 to clamp the aforesaid rods or pins 3. By this means the smaller gage may be readily set in a desired position between and upon two angularly related larger gages, so that the rods or pins 3 of such 90 smaller gage may be pushed into engagement with the surface of the object to be profiled that could not otherwise be reached by the rods or pins 3 of the larger gage. The clamping of the larger gages together, 95 by means of the interposed smaller gage, also serves to somewhat stiffen the larger gages in relation to one another.

Changes may be made in the details of construction and arrangements of parts set 100 forth, within the scope of the appended claims, without departing from the spirit of the invention.

Having now described my invention what I claim is:—

105

1. A profile gage comprising a pair of opposed members, rods or pins located between and transversely with respect to said members, means for clamping said members together with respect to said rods or pins, 110 and a resilient retainer comprising spaced rubber tubes between one of said members and said rods or pins for frictionally retaining the latter in set positions, and a gutter-like strip secured within said member 115 and receiving said tubes.

2. A profile gage comprising a pair of members secured together one opposing the other, parallel rods or pins therebetween, and means for retaining said rods or pins 120 in set positions, one of said members having at one end a casting provided with holes, screws received in said holes, and the other of said members having at the other of its ends a casting provided with slots adapted 125 to receive the screws of another gage, combined with another gage whereby said gages may be retained united in set positions.

3. A profile gage comprising a pair of members secured together one opposing the 130

other, parallel rods or pins therebetween, means for retaining said rods or pins in set positions, another gage and means at the ends of the gages for securing two or more 5 gages together in set positions, combined with a smaller gage provided with adjustable rods or pins adapted to fit between said two gages, the smaller gage having means for detachably securing it to and between 10 the rods or pins at the adjoining ends of said two gages.

4. A profile gage comprising a pair of members secured together one opposing the other, parallel rods or pins therebetween, 15 means for retaining said rods or pins in set positions, another gage and means at the ends of the gages for securing two or more gages together in set positions, combined

with a smaller gage provided with adjustable rods or pins adapted to fit between two larger gages, the smaller gage having a clamping member provided with means opposed to a member of the gage for clamping the smaller gage upon rods or pins of and adjacent the ends of said two gages, said 20 smaller gage having a threaded stud passing freely through said clamping member, and a nut on said stud coating with said clamping member.

Signed at New York city, in the county 30 of New York, and State of New York, this 19th day of June, A. D. 1914.

JAMES H. REINHARDT.
